UNITED STATES PATENT OFFICE.

WILLIAM F. DICKEY, OF LYNCHBURG, VIRGINIA.

CUT-OFF DEVICE.

1,036,807.

Specification of Letters Patent. Patented Aug. 27, 1912.

Application filed August 9, 1911. Serial No. 643,158.

To all whom it may concern:

Be it known that I, WILLIAM F. DICKEY, a citizen of the United States, residing at Lynchburg, in the county of Campbell and State of Virginia, have invented new and useful Improvements in Cut-Off Devices, of which the following is a specification.

This invention relates to an improved cut-off device adapted for use in dispensing 10 quantities of dry substances, such as powders, salts or granular masses, and has for an object to provide a device of this nature for application to the inlet openings or necks of bottles, jars, cans, and the like, the device 15 being so constructed as to form a closure for the bottle or other article to which the device is applied.

The invention further designs to provide a stopper attachment for a bottle, or the like, 20 having a compartment through which the contents of the bottle must pass, and which may be closed at either end to confine a quantity of the material in the stopper to be discharged freely when the bottle is inverted.

The invention essentially comprises an elongated hollow stopper for a bottle having spaced cut-offs adjacent its ends, which are arranged in offset relation with respect to 30 each other for alternately closing and opening the stopper at its opposite ends, providing a compartment between the cut-offs in the stopper which may be alternately opened and closed at its opposite ends to receive and 35 to discharge the contents of the bottle as the same pass through the stopper, the stopper carrying a thumb lever connected to the cut-offs to actuate the same by the hand supporting the bottle.

For a more complete understanding of the 40 invention, and to specifically bring out other and further objects, reference is had to the following description and the accompanying drawings disclosing one embodiment of the 45 invention.

In the drawings, Figure 1 is a front elevation of a bottle having the improved cut-off device applied thereto. Fig. 2 is an enlarged detail vertical central section through 50 the device, the front half thereof being broken away. Fig. 3 is a detail enlarged rear elevation of the device. Fig. 4 is a horizontal section on the line 4-4 of Fig. 3, showing the normal position of the device

in which the inner cut-off is closed. Fig. 5 is a similar view disclosing the cut-offs in reversed position for filling the stopper.

In the drawings, disclosing one embodiment of the invention, 10 designates a container, disclosed in the present instance in 60 the form of a bottle having a suitable neck 11.

The improved cut-off device comprises an elongated tubular body member 12 of a size adapting it to fit loosely within the neck 11 of the container, the member 12 carrying 65 about its inner or lower end a tapering ring 13 of yielding material, preferably cork, adapted to bind in the neck 11 and securely hold the tubular member 12 in position.

The tubular body member 12 is open at its 70 opposite ends, and is provided toward said ends with upper and lower slots 14 and 15 disposed in the opposite side walls of the tubular member and extending peripherally half way around the same. The upper and 75 lower cut-offs 16 and 17 are arranged to slide within the slots 14 and 15 respectively, each one of the cut-offs being in the shape of a flat disk and conforming in size to the inner wall of the tubular member 12 80 against which it is adapted to snugly engage in order to close the passage through the tubular member. Each cut-off is provided with a tangential extension or tongue 18 extending through one end of the slot 85 when the cut-off is closed, the outer edge of the tongue 18 of the upper cut-off 16 being rolled preferably downwardly for fixed engagement about a combined operating and supporting arm 19. The lower cut-off 17 90 has its tongue 18 preferably rolled upwardly about a combined operating and supporting arm 19'. The arms 19 and 19' form turned over opposite ends of a rock shaft 20 arranged against one side of the tubular body 95 member 12 in parallelism with the longitudinal axis of the same. The inner or lower arm 19' is continued beyond the tongue 18 attached thereto, and is curved slightly inward substantially concentric to the tubular member 12, providing a thumb lever 21.

A head or enlargement 22 is arranged upon the extremity of the lever 21 for the reception of the thumb or finger of the operator when rocking the shaft 20.

The shaft 20 is supported against the side of the tubular member 12 in any adaptable and desired manner, preferably by a

bracket. The bracket disclosed in the present instance comprises a flat metallic strip 23 riveted or otherwise permanently secured in fixed relation, and longitudinally against the side of the member 12, the strip 23 having its opposite ends turned outwardly to provide a pair of vertically spaced outstanding and registering ears 24, suitably apertured for rotatably receiving the ends of the rock shaft 20. It will be noted, particularly from Figs. 3 and 4, that the arms 19 and 19' are turned outwardly from the ends of the rock shaft 20 at an obtuse angle, and that they thereby so support the cut-offs 16 and 17 that the latter enter the slots 14 and 15 and alternately close the passage through the tubular member 12.

Normally the lower cut-off 17 is adapted to be closed, as is disclosed in Figs. 1, 2 and 4, and for the purpose of insuring the sealing of the container 10 an annulus 25 is positioned within the tubular member immediately below the cut-off 17, and has its upper edge flush with the lower marginal edge of the slot 15. The annulus 25 is made of a yielding material, preferably cork, so as to yieldingly bind and support the lower cut-off 17 when closed. A reinforcing spring ring 26 is preferably employed, and is carried against the inner yielding wall of the annulus 25 and presses against the latter the inner wall of the tubular member 12 to insure the tight fitting of the annulus therein.

This improved cut-off device is particularly adapted for use with large bottles containing a number of doses of headache powder or the like. The space or compartment within the tubular member 12, and defined by the upper and lower cut-offs 16 and 17, is adapted to contain approximately one dose of powder. In use, the thumb lever 21 is normally placed in toward the member 12, closing the lower cut-off 17 which rests upon the upper edge of the annulus 25. In this manner the contents of the bottle are protected from the action of the air by the effective sealing of the lower cut-off by the annulus 25. When it is desired to discharge the contents from the container 10, the operator grasps the container and places a thumb upon the head 22 and swings the thumb lever 21 outwardly from the tubular body member 12. This action rocks the shaft 20, withdrawing the cut-off 17 out through the slot 15 and bringing the opposite or outer cut-off 16 in through the slot 14. The lower end of the compartment is now open while its upper end is closed. The container is now inverted, while the cut-offs are held by the thumb in this position to hold the inner end of the stopper open. The mouth or outer end of the member 12 is held over a glass, or other receptacle, into which the powder is to be dropped, and the thumb

lever 21, by a slight pressure, is snapped inwardly to its full extent, closing the inner end of the stopper to hold the contents within the container, and opening the outer end of the compartment to admit of the discharge of the material into the glass. When the inner cut-off 17 is only half closed, the outer cut-off 17 is half open, and the quantity of material between the cut-offs begins to flow from the stopper, leaving a space in the compartment which is filled for a short time by the flow of the contents from the container. This peculiarity in construction of the device admits of the discharging of an extra or large dose of material by simply closing the cut-off 17 slowly. Ordinarily slight pressure of the thumb completely closes the inner end of the compartment before any appreciable amount of the material escapes past the inner cut-off 17, the compartment between the two cut-offs, therefore, being practically a definite measure.

It will be noted from the drawings that the cut-offs 16 and 17 are so arranged upon the rock shaft 20 that they are not completely withdrawn from the slots 14 and 15, but that their inner edges project slightly into, and are confined within, the slots to hold the cut-offs in their true position and guide the same in their opening and closing movements.

It is readily seen that this cut off device may be adapted to various other uses than herein described, and that specific variations may be made in the construction of the device within the scope of this invention.

Having fully described my invention what I claim is:

1. A cut-off device comprising a tube having slots in its opposite sides, disks slideable through the slots adapted to close the opposite ends of the tube, a shaft journaled at one side of the tube and having connection at its ends with the disks to reversely move the latter, and an annulus of yielding material fitting snugly in the lower end of the tube and having its upper edge flush with the lower marginal edge of the lower slot to seal the tube when the lower disk is closed.

2. A cut-off device comprising a straight elongated tube, a tapering annular member carried about the lower end of the tube adapted to wedge into the neck of a bottle, said tube having at its opposite sides and adjacent its ends circumferential slots extending half-way around the tube, disks slideable through the slots adapted to fit snugly against the inner wall within the tube and close the opposite ends thereof, said disks having extensions at their outer sides extending outwardly from one side of the tube, a bracket disposed vertically against said side of the tube, and a rock-shaft journaled vertically in the bracket and having

its ends turned oppositely and connected to said extensions whereby the disks are adapted for reverse movements, and a thumb-piece used with the rock-shaft adapted to 5 alternately open and close the opposite ends of the tube.

In testimony whereof I have hereunto set

my hand in presence of two subscribing witnesses.

WILLIAM F. DICKEY.
